The ornamental design for a “hand-held electronic device,” as shown and described.

DESCRIPTION

FIG. 1 is a front, top and left-side perspective view of the hand-held electronic device;

FIG. 2 is a front plan view of the device shown in FIG. 1; FIG. 3 is a rear plan view of the device shown in FIG. 1. The broken line of FIG. 3 is for illustrative purposes only and forms no part of the claimed design.

FIG. 4 is a front elevational view of the device shown in FIG. 1;

FIG. 5 is a bottom elevational view of the device shown in FIG. 1;

FIG. 6 is a left side elevational view of the device shown in FIG. 1; and,

FIG. 7 is a right side elevational view of the device shown in FIG. 1.

The broken line showing of FIG. 3 is for illustrative purposes only and forms no part of the claimed design.
